HANDLE FOR DISPOSABLE DRINKING CUPS OR THE LIKE

Frederick Lawrence Meagher, Blairstown, N.J., assignor to American Can Company, New York, N.Y., a corporation of New Jersey

Filed July 23, 1963, Ser. No. 75,931

Term of patent 14 years

(Cl. D44—29)

FIG. 1

FIG. 5

FIG. 3

FIG. 2

FIG. 4

FIG. 8

FIG. 7

FIGURE 1 is a perspective view of a handle for disposable drinking cups or the like, showing my new design;

I claim:

The ornamental design for a handle, for disposable drinking cups or the like, substantially as shown.
